DESIGN FOR A GAS FLOW METER

Russell H. Ladd, San Francisco, Calif., assignor
to Victor Equipment Company, San Francisco,
Calif., a corporation of Delaware

Application April 29, 1946, Serial No. 129,083

Term of patent 14 years

(Cl. D52—1)

To all whom it may concern:

Be it known that I, Russell H. Ladd, a citizen
of the United States and a resident of the city
and county of San Francisco, State of California,
have invented a new, original, and ornamental
Design for a Gas Flow Meter, of which the fol-
lowing is a specification, reference being had to
the accompanying drawing, forming a part
thereof.

Fig. 1 is a perspective view of a gas flow meter
showing my new design. The view shows the
front and one side and is taken looking down also
showing the top.

Fig. 2 is a view similar to that of Fig. 1 but
taken looking up and showing the opposite side,
edge, and the bottom.

I claim:

The ornamental design for a gas flow meter,
substantially as shown.

RUSSELL H. LADD.
